BREECH-LOADING ORDNANCE.

1,327,087.

Specification of Letters Patent.

Patented Jan. 6, 1920.

Application filed June 25, 1918. Serial No. 241,899.

To all whom it may concern:

Be it known that we, Sir ARTHUR TREVOR DAWSON, knight, and Sir GEORGE THOMAS BUCKHAM, knight, both subjects of the 5 King of Great Britain, residing at Vickers House, Broadway, Westminster, in the county of London, England, have invented certain new and useful Improvements in or Relating to Breech-Loading Ordnance, 10 of which the following is a specification.

This invention relates to semi-automatic guns of the kind in which the breech closing spring and the means for actuating the breech mechanism automatically are rendered 15 inoperative by suitable controlling devices when the gun is converted from the semi-automatic to the quick firing condition. In these guns the said devices have been separately actuated so that conversion 20 from the semi-automatic to the quick firing condition has necessitated two separate operations, one serving to render the breech closing spring inactive and the other serving to render the automatic actuating means inoperative. 25 Similarly in converting from the quick firing to the semi-automatic condition, two separate operations have been required, one serving to render the breech closing spring active and the other serving 30 to render the automatic actuating means operative.

According to the present invention the device for controlling the breech closing spring and the device for controlling the 35 automatic actuating means are connected together in such manner that a single operation serves to render the breech closing spring inactive and the automatic actuating means inoperative for the quick firing 40 condition and a single operation also serves to render the said spring active and the said means operative for the semi-automatic condition. In this manner we not only save time in the conversion from one condition to 45 the other, but we also avoid the liability of the gunner omitting to perform the aforesaid separate operation for rendering the automatic actuating means operative or inoperative as the case may be.

50 In order that the said invention may be clearly understood and readily carried into effect we will describe the same more fully

with reference to the accompanying drawings, in which:—

Figures 1, 2 and 3 are respectively a left 55 hand side elevation, a rear elevation and a plan of the breech end of a gun provided with our improvements.

Figs. 4 and 5 are right hand side elevations showing the parts set respectively for 60 the semi-automatic condition and for the quick firing condition.

Fig. 5^a is a side elevation showing a cylinder which carries the aforesaid breech closing spring, displaced into a position for dis- 65 mantling.

Fig. 6 is a section taken approximately on the line 6—6 of Fig. 2.

Fig. 7 is a local section taken approximately on the line 7—7 of Fig. 4 and drawn 70 to an enlarged scale.

Fig. 8 is a local section taken approximately on the line 8—8 of Fig. 4 and drawn to an enlarged scale.

Fig. 9 is a section taken approximately 75 on the line 9—9 of Fig. 4 and drawn to an enlarged scale, and

Fig. 10 is an enlarged side elevation of the aforesaid device for controlling the breech closing spring, viewed from the left 80 hand side of the gun.

A is the breech end of the gun, A' is the sliding breech block mounted to move vertically. A² is the breech actuating handlever and A³ the actuating shaft to which 85 this handlever is connected. B is the semi-automatic cam and B' is the pawl, pivoted at b' to the gun cradle, for operating this cam as is well understood. C is the breech closing spring. D is the aforesaid device 90 for controlling this spring and E the aforesaid device connected to the device D and adapted to render the pawl B' inoperative or allow it to become operative as required.

In the example shown the aforesaid cam B 95 is fixed to or made integral with the breech actuating handlever A² and the shaft A³, and the aforesaid breech closing spring C is disposed in a cylinder C' and bears against a plunger c the lower end of which engages 100 with a pin c' detachably carried by the cam B so as to form a crank pin. The cylinder has a lateral projection C² near its end remote from the plunger c and this projection

works in a recess α in the breech end of the gun. The said projection is constituted by a T-shaped head having curved surfaces and the recess is undercut to provide grooves in which this head works.

In this manner the cylinder C' can be readily detached (after the pin c' has been removed) by displacing it through an angle of 90 degrees to bring the flat sides of the 10 said T-shaped head into coincidence with the narrow portion or neck of the recess α , as shown in Fig. 5^a, thereby enabling the said head to pass through this narrow portion and the cylinder to be removed.

15 The aforesaid device D is in the form of a plate pivoted at d to the breech end of the gun above the cylinder and engraved with the two working positions "QF" and "SA." The pivot pin d of the plate is integral there- 20 with and is detachably connected to the gun by a bayonet joint. This plate D carries a pin D' connected preferably by a bayonet joint to one end of a link F, the said pin also forming a milled handle by which the plate 25 can be moved about its pivot d . The other end of the link has a lateral projection F' provided with a circular head working in an undercut recess α' of key-hole formation in the breech end of the gun and has a toe- 30 piece (constituting the aforesaid member E) by means of which the pawl B can be put out of action when the gun is to be used under quick firing conditions (see Fig. 5). The plate D is formed with a groove d^2 concentric with the pivot d of the plate in 35 which groove works a spring controlled plunger D² (see Fig. 8) carried by the gun. At each end of this groove a recess d^{2x} (see particularly Figs. 8 and 10) is provided for 40 the reception of the plunger which thus retains the plate in the desired position for the quick firing or the semi-automatic condition of the gun. The said plunger is disposed in a recess α^2 (see Fig. 8) in the breech end of 45 the gun and is actuated and retained in position by a milled pin D³ which is screwed into, and limits the movements of, the plunger. A small hole d^3 (Figs. 4, 5, 8 and 10) is drilled in the plate through which a tool 50 can be inserted to displace the plunger for dismantling purposes. To dismantle, the pin D³ is removed, and the plate D is moved beyond the "QF" position to release the bayonet joint of the pin d and permit of the 55 plate D being removed.

When the breech is opened under quick firing conditions the cylinder C' containing the breech closing spring C moves unobstructed in its path so that the spring is not energized during this operation (see Fig. 5) 60 the aforesaid plate D being so shaped that when moved to the quick firing position shown by Fig. 5, it leaves the head of the cylinder C' and at the same time raises the 65 link F; the toe-piece E on the lower end of

the link by meeting the pawl B' lifts the latter upward about its pivot b' and thus puts it out of action; during the run-out movement of the gun the toe-piece E first meets the pawl and the latter is thus lifted 70 clear of the cam B.

When converting to the semi-automatic condition after the gun has been loaded under quick firing conditions, the plate D comes into contact with the head of the cylinder C' (see Fig. 4), lowers the link F and releases the pawl B' so that during the run-out movement of the gun the pawl, by engaging with the cam B, opens the breech mechanism and compresses the breech closing spring C, the breech mechanism being held in its open position by claws g on the extractor G engaging with projections on the breech block (see Fig. 6); on again loading the gun, the extractor is carried forward 85 by the cartridge case, thereby moving the claws g out of engagement with the said projections on the breech block, thus releasing the breech mechanism which is closed by the spring C. 90

It is to be observed that the assembling and dismantling of the various parts may be easily and speedily accomplished by displacing them beyond their working positions and then moving them out of the recesses in 95 which they work. It is also to be observed that for the first round to be fired under semi-automatic conditions the breech can be opened without this operation energizing the aforesaid breech closing spring. 100

What we claim and desire to secure by Letters Patent of the United States is:—

1. In breech loading ordnance of the semi-automatic type, the combination with the breech closing spring, a device for rendering said spring inactive for quick firing working of the gun, means for actuating the breech mechanism automatically during semi-automatic working of the gun and a device for rendering said means inoperative for the quick firing working, of means for connecting said devices together in such manner that a single operation serves to render the spring inactive and the automatic actuating means inoperative for the quick 105 firing working of the gun and a single operation also serves to render the said spring active and the said actuating means operative for the semi-automatic working of the gun. 11

2. In breech loading ordnance of the semi-automatic type the combination with the breech closing spring, of a device which when set to a position for the semi-automatic working of the gun, serves as an abutment for one end of said spring and when set to a position for the quick firing working of the gun no longer acts as such abutment, means for actuating the breech mechanism automatically during the semi-automatic 115

- working of the gun, a device for rendering said means inoperative for the quick firing working of the gun and operative for the semi-automatic working of the gun and 5 means for connecting said devices together in such manner that conversion from the semi-automatic to the quick firing working condition or vice versa can be performed by a single operation.
- 10 3. In breech loading ordnance of the semi-automatic type, the combination with the breech closing spring, of a device which, when set to a position for the semi-automatic working of the gun, serves as an abutment for one end of said spring and when set to a position for the quick firing working of
- the gun no longer acts as such abutment, a pawl and a cam for actuating the breech mechanism automatically during the semi-automatic working of the gun, a device for 20 holding said pawl inoperative for the quick firing working of the gun and allowing it to become operative for the semi-automatic working of the gun and a rod connecting said devices together so that they can be 25 moved simultaneously to the semi-automatic or to the quick firing position.

In testimony whereof we affix our signatures.

ARTHUR TREVOR DAWSON.
GEORGE THOMAS BUCKHAM.
